DELAWARE.

TYPE-WRITING MACHINE.

1,063,624.

Specification of Letters Patent.

Patented June 3, 1913.

Original application filed August 22, 1910, Serial No. 578,457. Divided and this application filed May 3, 1911. Serial No. 624,828.

To all whom it may concern:

Be it known that I, CHARLES H. VOGEL, a subject of the King of England, residing in Vancouver, in the county of Vancouver, 5 Province of British Columbia, Dominion of Canada, have invented certain new and useful Improvements in Type-Writing Machines, of which the following is a specification.

10 This invention relates to means for feeding and returning the paper carriage of a typewriting machine, and this application is a division of my application No. 578,457, filed August 22, 1910.

15 The principal object of the invention is to provide simple and efficient means for exerting a constant and uniform tension upon the carriage, to advance it in its feeding movement, and also to enable the carriage to be easily returned from any point at the will of the operator.

In carrying out my invention, I employ a pneumatic cylinder, with a piston connected to the typewriter carriage. Compressed 25 air normally admitted by a valve to one end of the cylinder, advances the carriage for its feeding movement. By depressing a special control key, the valve is moved to reverse the air pressure on the piston, which 30 then returns the carriage.

In the accompanying drawings, Figure 1 is a partial section and front elevation showing the pneumatic device attached to a typewriter carriage. Fig. 2 is a left side view 35 of the typewriting machine, indicating my pneumatic device in position, and illustrating the key connection for controlling the carriage.

40 A carriage 1 is guided at the rear on rail 8^a, and has a rack 21 pivoted to the carriage at 22 and engaging an escapement pinion 23 associated with an escapement wheel 20. I attach a rod 2 to the carriage 1, to extend in the direction of travel of the carriage, and provide said rod with a piston 3 to reciprocate in a pneumatic cylinder 4 secured to the main frame 8 of the typewriting machine by a bracket 6.

45 Fig. 1 shows the normal position of a valve 11, which controls the admission of air to the cylinder. The air is normally admitted to air chest 12 through an inlet 17, and from air chest 12 passes through port 15 into the end of the cylinder adja-

cent to the carriage 1. The valve is held 55 in this position by a compression spring 14 which thrusts against the vertical arm of a bell-crank 10 connected by stem 10^a with valve 11. The air pressure on the right of the piston exerts a pull on the carriage 1, in 60 letter-feeding direction. The opposite end of the cylinder 4 is open to the atmosphere through port 13, exhaust passage 16, and outlet 18. In order to return the carriage from any point at the will of the operator, 65 I provide a key 7 extending from keyboard 24, fulcrumed at 25, and connected by a link 9 with the horizontal arm of the said bell crank 10. By depressing this key, the bell crank will rock to the right and draw 70 valve 12 to the right, so as to admit air through port 13 to the left end of the cylinder, and open port 15 to exhaust. The pressure on the piston instantly returns the carriage. By releasing the key just before the 75 carriage is completely returned, spring 14 will return the valve to its normal position, and air will be admitted in front of the piston, to cushion the carriage as it is arrested. As the return of the key 7 from 80 its depressed position, and therefore the point in the travel of the carriage at which the valve is reversed, is under the control of the operator, the return movement of the carriage can be arrested at a point corresponding with the speed at which the carriage is being returned. For example, when 85 the carriage is returned from an intermediate position, the momentum of the returning carriage will be less than when returned 90 after writing a full length line. The key should therefore be released at a later point in the return travel of the carriage corresponding to the comparatively short distance through which it travels while being 95 brought to rest. The return of the valve being under the control of the operator also permits the carriage to be stopped at any intermediate position in its return movement. Moreover, the operator may reduce 100 the pressure on the key sufficiently to permit a partial return of the valve and thereby throttle the fluid and thus reduce the speed of the carriage. In this way the carriage may be gradually slowed down and 105 brought to an easy stop as its return movement is completed, or may be slowly returned to any intermediate position. The

movement of the valve is limited by a stop 10^b in the path of the vertical arm of bell crank 10. When the pneumatic mechanism is operating as a tension device, to feed the carriage, the pulling force upon the carriage is constant and uniform throughout the entire travel of the carriage.

Having now described my invention, I claim:

- 10 1. A typewriting machine having a carriage in combination with a pneumatic cylinder, a piston rod actuated thereby and attached to said carriage, a valve coöperating with said cylinder, means for normally holding said valve in a position to cause said piston rod to advance said carriage in the letter-feeding direction, a key for actuating said valve to cause said piston rod to move said carriage in the reverse direction, and 15 means to return the key and valve whenever the key is released whereby the point at which the return movement of the carriage is arrested is under the control of the operator.
- 20 2. In a typewriting machine, the combination of a traveling carriage, pneumatic means for moving the carriage in either direction, controlling mechanism comprising a key operable to supply pneumatic pressure for returning the carriage, and means to automatically reverse the controlling mechanism whenever the key is released and sup-

ply pressure to the carriage in letter-feeding direction.

3. In a typewriting machine, the combination with a traveling carriage, of a cylinder, a piston therein, a connection between the piston and the carriage, a reversing valve to admit fluid pressure to either side of the piston, a controlling key, connections from the key to the valve for moving the valve to a position to admit pressure for returning the carriage when the key is depressed, and means operable automatically when the key is released to reverse the valve and apply pressure for moving the carriage forward.

4. In a typewriting machine, the combination with a machine frame, of a traveling carriage, a cylinder supported on the machine frame, a piston working in the cylinder, a piston rod connecting the piston to the carriage, a reversing valve movable into positions to admit pressure at either side of the piston, a spring to move said valve into position to admit pressure to operate the carriage in letter-feeding direction, a finger key, and connections between the key and valve for moving the latter against the tension of the spring into position to admit pressure to return the carriage.

CHARLES H. VOGEL.
